TUNING INDICATOR CIRCUIT

Karl Steimel and Kurt Mie, Berlin, Germany, assignors, by mesne assignments, to Telefunken Gesellschaft fur Drahtlose Telegraphie m. b. H., Berlin, Germany, a corporation of Germany

Application October 8, 1937, Serial No. 167,977
In Germany October 8, 1936

1 Claim. (Cl. 250—40)

Often it is customary to render visible the presence of voltage by optical means. These means may consist, for instance, of a glow discharge tube which becomes ignited only when the voltages exceed a certain limit. It is already known to use fluorescent electrodes for such optical voltage indicators, said electrodes radiating light when impinged upon by electrons, and furnishing a luminous pattern varying as to position or shape. A known embodiment of this principle of indication utilizes a directly heated glow cathode extending in one direction, furthermore a plate-shaped control electrode in parallel thereto and a fluorescent anode likewise arranged parallel to said cathode and placed in back of the grid. The voltage drop through the directly heated cathode produces in the longitudinal direction of the system continuously varying field conditions. A negatively biased grid blocks, according to the value of its biasing potential, the entire electron stream passing to the anode, or only the part at which the grid has sufficiently high negative bias relative to the corresponding cathode sections. If thus the control potential at the grid is properly made dependent on the voltage to be indicated, a luminous band appears on the anode whose length corresponds to the voltage.

The main disadvantage of this arrangement resides in that it can only be used for heating with direct current, since a fixed potential drop extending in the same direction is necessary at the glow cathode. Hence the majority of conceivable possibilities of usage cannot be considered for this arrangement. The further disturbing factor in this arrangement is that the glow cathode is not optically shielded, so that eventually the luminous pattern appearing on the anode is optically interfered with by the light of the cathode.

In another mode of construction a directed electron stream is utilized, deviated in dependence of the voltage to be indicated. However, such an arrangement requires a complicated cathode arrangement for the production of the concentrated electron ray thus involving high cost. Furthermore, in many cases it is not advisable to render the voltage recognizable simply by the change in position of the indicating light spot.

In a still other indicating arrangement an indirectly heated cathode is employed so that this arrangement can also be used for alternating current. In the preferred embodiment this cathode is surrounded coaxially by a cylindrical or coni-

cal glow anode, and the angular range of light on this anode is determined by the voltage of control electrodes arranged within the anode. The control electrodes preferably have the shape of a pin, or sharp edge, and in general they have high positive control potentials applied thereto. The voltages required for a satisfactory control are so high, that is, the indication has such a low sensitivity that the control potentials ordinarily employed in radio apparatus are insufficient and must first be increased. Therefore, in the said arrangement, in the same bulb also an amplification system of ordinary construction is arranged below the same cathode, and by means of which the control potentials are amplified for the necessary values. This additional amplifying system obviously increases the cost of such an indicating arrangement. However, the amplifying system may in this case, and to a certain extent also be used at the same time for other purposes.

Ordinarily, in the above-described arrangement the anode of the amplification part is extended into the indicating part for instance by extending the anode supporting wires into the other part. But suggestions have also been made to extend the control electrode of the amplifying system into the indicating system. Tests have proven that also such arrangement reveals a rather low sensitivity, and requires high control potentials. The comparatively low sensitivity of the above-described arrangement is due to the fact that the electrons already have a very high velocity at the place of deviation. The control electrodes shaped as pins, or sharp edges, in fact have but a small effect upon the field intensity of the cathode so that the electron emission is substantially determined by the plate potential. Consequently, the electrons undergo immediate acceleration after having been emitted, and thus they have already a considerable velocity in the vicinity of the control electrodes.

On the basis of the teaching that the field intensity as well as the potential must be maintained low at the place of control so as to maintain low the velocity of the electrons to be controlled, the present invention provides means by which this can be accomplished. In accordance with the present invention, in an optical indicating arrangement for voltage, in which an electrode which becomes fluorescent by the action of impinging electrons, and the voltage to be measured is indicated by the extent of the angular range on which light appears, the control element is so designed, or such additional means are provided, that a control space is formed which sur-

rounds the cathode, and the potential and field intensity are decreased at the place of control.

This end is attained in the simplest manner by means of a grid surrounding the cathode. Such 5 grid shields the cathode against the anode so that only a portion of the plate potential remains directly active on the cathode, while the field intensity on the cathode is substantially determined by the potential of the grid. Thus, if a potential 10 is impressed upon the grid which in the average is far below the plate potential, for instance cathode potential or a negative potential, the electrons emitted from the cathode move with comparatively low velocity through the path leading to 15 the grid, and only after arriving in back of the grid are they accelerated to the point at which they reach the velocity necessary for exciting fluorescence. It was found that the control potentials of the order of a few volts as normally 20 used in radio apparatus for the fading control or the like, are sufficient to cover the entire angular range.

At the same time such a grid surrounding the cathode offers the possibility that aside from the 25 control of the angular range the intensity can be controlled. Thus, there is possible the following indication system which is very favorable from a psychological point of view: Without voltage the optical voltage indicator remains dark, at low 30 voltages it shows a brightening up, and at maximum voltage there results a sharply limited luminous surface whose angular range varies in dependence on the value of the indicated voltage. Such simultaneous control of the angle and intensity 35 is not possible with the known arrangements and offers a particular advantage of the arrangement according to the present invention.

Furthermore, the diminution of the potential near the cathode by the introduction of the grid 40 has the following, technically very important advantage.

To excite the fluorescent coating of the plate so that it emits visible light, requires relatively 45 high voltages, but only small currents. If the currents are increased, the life of the coating is reduced. Therefore, it is necessary to have the currents limited.

Without a grid near the cathode the current 50 can be limited only by the saturation of the cathode. This method of limiting the current however has essential disadvantages.

Difficulties already arise during activating the cathode for the coating and the cathode may be deteriorated by the heavy currents or by occasional 55 outbursts of gas during the process.

Images of non-emitting spots, which happen to be on the cathode, will be clearly visibly projected on the plate, disturbing the pattern of light thereon.

Finally a saturation limited current is highly 60 dependent on the temperature of the cathode. So changes in filament voltage, which cannot be avoided in practice, will produce similar changes in plate current and brightness of the light pattern, which are very troublesome in certain circuit connections.

By introducing the grid these disadvantages 65 are completely avoided, because in this case the current is limited by space charge, which can build up in consequence of the said diminution of the potential near the cathode by the grid.

These advantages achieved by the introduction 70 of the grid during the activation of the cathode and during the life of the device are so important, 75 that they warrant the introduction of the grid

even if this grid is not to be used to control the current, but is held on a fixed potential such as the cathode potential.

Since it is desirable that at the last control of the angle a constant density of the light be maintained, it will be of advantage if the control elements determining the angle are removed as far as possible from the cathode. Thus the control elements shaped as pins, or sharp edges, will have to be arranged in the vicinity of the grid electrode either inside or outside the same. It is even possible to have the control pins at the place of the grid supports so that practically the grid acts simultaneously as a shield and as a control element. The shielding action is taken over by the grid winding, while the angle control is exerted by the grid bridges.

For a better understanding of the invention reference will now be made to the accompanying drawings wherein Figs. 1a, 2a and 3a illustrate 20 various constructions of the visual indicator portion of electron tubes according to the present invention. Figs. 1b, 2b and 3b are the respective plan views of Figs. 1a, 2a and 3a. Figs. 4, 5 and 6 represent partial circuits which illustrate 25 various connections of the electrodes constituting the visual indicator tubes, and Figs. 7 to 16 illustrate more complete circuits showing further arrangements according to the invention.

In Fig. 1a, 1 designates the glow cathode, 2 represents the pin-shaped control electrodes, 3 is the grid acting as a screen, 4 is the fluorescent anode having the known conical shape and supported by the members 5. The entire system is supported by an insulating disk 6 inserted into the tube 7. In Fig. 1b the lines 8 represent the angular range illuminated by the impinging electrons on the anode. Fig. 2a differs from Fig. 1a only by the omission of special controlling pins, the grid supports 3 taking over the control of the angular range. These supports may eventually be thicker than is required. In both figures in place of the pin-shaped control bridges as shown, edge-shaped or band-shaped control members may be employed. The conical anode may, also, 45 be replaced by one having a cylindrical, or similar, shape.

For indicating by light, only a small electron current is necessary. The required energy is so low, and the dimensions of the indicating system 50 can be so small, that a voltage indicator according to the invention can be combined without difficulty with an ordinary amplifying system for radio purposes, or the like. The combination, according to a further feature of the invention, 55 of a voltage indicator with one or several ordinary discharge systems represents a reduction in cost as compared with the above-described known arrangement, because the other systems combined with the indicating section are available for other purposes also. Hence, the indicating section does not require a special bulb.

Fig. 3a shows such a construction combined with an ordinary triode. The reference characters for the voltage indicator are the same as in the previous figures. In the amplifying section, 9 represents the anode, and 10 is the control grid. As seen from the figure, in a manner similar to the known arrangement, the anode supports 2 are extended into the indicating section, and also serve for controlling the angular range. They are arranged outside the control grid, contrary to Fig. 1a wherein the control pins 2 are inside the grid.

In order optically to shield the glow cathode 75

thereby facilitating the viewing, the grid is suitably closed up by a cap 11 at the end pointing towards the place of viewing. Such cap, or similar light stop, may as is obvious also be provided in the arrangement according to Fig. 1a or 2a. Since the cap is fixedly secured to the grid, and the grid has in general a low potential, danger exists that the cap will cause too high a decrease of the electron stream passing to the anode, thus obtaining only a narrow luminous stripe. In order to prevent this condition the grid can be extended in this direction to such an extent beyond the system that the field caused by the cap does not produce a detrimental effect.

15 In place of the triode system shown, obviously any other system may be used. Furthermore, it is not necessary to provide the control electrodes in pairs, only a single controlling pin may be provided instead. On the contrary a greater 20 number of pins may be arranged. If the indicating section is combined with an amplifying system containing more than three electrodes, then any other electrode may be extended as a 25 control element into the indicating space. In all cases, in place of the anode the control grid may be used for the additional control of the angle.

30 As already pointed out above, the amplifying system is absolutely independent of the indication section and may be utilized for any other purpose. This is also true if one of the amplifier electrodes protrudes into the indicating section. In such a case it is always possible so to arrange the other electrodes, especially the grid, that the 35 additional control exerted by the extended electrode amounts to only a small part, while the main control is effected for instance by the bridges of the grid. This independence of the two systems offers a multitude of possibilities of 40 connections representing a special characteristic feature of the arrangement according to the invention.

45 The combination of circuits resulting from the combining of the two systems can be grouped into four different cases. In the case I, the amplifying section is connected as a resistance amplifier for the control potential, and directly controlled by the anode extensions protruding into the indicating section, while the grid serving as a screen may be maintained at a fixed potential such as by connecting it directly with the cathode, or else it may have applied thereto a variable potential which may be manually controlled. This case is similar to the circuit used 50 in the last of the known arrangements herein mentioned. In the case II, the two systems are independent of each other except for the last-mentioned limitation. The control of the indication section is carried out solely by the grid arranged within said part, and which for the sake of convenience shall be termed a regulation grid. To this end, the grid has applied from any suitable place of the apparatus a control potential having the proper sense. This 55 place may be a preceding stage, or a subsequent stage, of the apparatus, or the stage proper which is combined with the indicating system. Contrary to case I, in this case, however, the control potential for the regulation grid is tapped from a resistor in the circuit of this stage, so that it will then also be available for other purposes. The case III represents the combination of case 60 I and II. It can be divided into the two sub-cases namely that (a) the two controls act in the same sense, thus supporting each other, and

that (b) the two controls are opposite whereby the control corresponding to the case I must have a much smaller influence than the control according to case II. The case IV resides in that the indicating section, having the appearance of a triode, is used at the same time for any other purposes.

10 In the circuit diagrams, the individual cases are elucidated by individual special examples. Figure 4 corresponds to the case I. The control 15 grid 1' of the amplifier section, represented as a triode, has applied thereto the control potential produced by a diode path, or by an audion, and which is amplified therewith. The anode 2' of this section has extensions 3' in the indication 20 part through which an angle control is carried out in accordance with a change of the control potential. The regulation grid 4' acting in this case as a screen is directly connected to the cathode 5'. However, as already stated, the potential of the regulation grid may also be controlled by manual means. 6' is the fluorescent anode.

25 Fig. 5 shows an example for case II, namely the sub-case in which the control potential applied to the regulation grid 4' is derived from the preliminary stage. In the example represented, the control potential is tapped from the screen grid potential V_s of the preliminary tube 30 by means of a potentiometer.

35 Fig. 6 likewise comes under case II. But in this figure the control potential for the regulation grid 4' is tapped at the cathode resistor which, in fact, carries the current passing in the 40 amplifying part. In the example shown the control potential is produced by a diode path. The remaining circuit corresponds with the ordinary arrangements. For the sake of elucidation it should simply be borne in mind that the resistor R_1 is connected with a positive voltage 45 source.

50 In the arrangement according to Fig. 7, the control of the tuning indicator tube M is used simultaneously according to Figs. 4 and 5. The radio or intermediate frequency is fed from the output of the preceding tube through the band pass filter B_f to the left plate of diode D. Said diode produces the control potential for the preceding tube through resistance R_7 . Simultaneously over resistance R_{10} audio frequency is derived from resistance R_7 by way of the elements R_{11} , C_4 and the volume control resistance R_5 which is A. C. grounded over condenser C_5 . A variable portion of the audio frequency voltage developed across R_5 is amplified by the audio 55 frequency tube N which is resistance-condenser coupled to the final stage in the usual manner. The grid 1' of the tuning indicator tube M is connected to the control potential for the preceding tubes over a filter element consisting of resistance R_6 and condenser C_1 . The necessary grid bias is applied to said grid simultaneously with the audio frequency tube N through the cathode resistances R_8 and R_9 bridged by condenser C_3 . Resistance R_8 furthermore effects a retarding of the control potential so that said potential and therefore also the indication does not begin before a given radio or intermediate 60 frequency amplitude is attained. Due to the connection of the grid 1' of the triode system of the tuning indicator tube M to the control potential, the potential of the control grid becomes more negative with increasing radio or 65 70 75

intermediate frequency of the diode D. As a result the plate current becomes smaller and the plate potential increases due to the smaller voltage drop across the plate resistance R_1 . This effects a broadening of the light angle through the light-control electrodes 3''. With increasing plate potential the potential of the regulating grid 4' taken off between resistances R_2 , R_3 also increases, whereby again a broadening of the light angle is brought about. Both controls over the control grid 1', on the one hand, and over the regulating grid 4', on the other hand, assist one another, and thus effect a high sensitivity beginning with a light angle of 0° up to about 160°. In addition to its function as a tuning indicator the tube M has a second purpose in the circuit just described. A sufficiently high negative potential is applied from the potential source S_p through resistance R_4 to the grid of the audio frequency tube N so that said tube is blocked. When radio or intermediate frequency is received the potential between resistances R_2 and R_3 becomes more positive as mentioned above, and thus also the potential between resistances R_3 and R_4 . At the instance where the negative bias of the regulating grid 4' becomes positive, grid current begins to flow whereby the high negative potential of the grid of the tube N is compensated and the blocking of said tube is terminated. As an aid the right-hand discharge path of the diode D is connected in parallel to the regulating grid.

Fig. 8 shows an arrangement somewhat similar to Fig. 7. In this case also tuning indicator tube M has two functions, namely, indication and removal of blocking of the control potential for silent tuning. Instead of the battery S_p of Fig. 7 a different cathode level of the tuning indicator tube and of the diode is used. In this case a multiple purpose tube D', (diode and triode) is employed in place of the tubes D and N in Fig. 7. Said level is produced by the biasing resistance R_9 which is bridged by condenser C_5 and is possible by having the cathode currents of multiple purpose tube D' and of tuning indication tube M pass through said resistance R_9 . At the same time, said level is applied to retardation of the control potential which is produced over resistance R_8 and which is fed to the preceding tube over resistance R_7 . The second or right-hand diode path is connected to the cathode over resistance R_{10} and is fed, through condenser C_4 , the radio or intermediate frequency potential derived from the output of the band-pass filter. Said diode path serves for the production of the audio frequency potential and also for the production of the control potential for the tuning indicator tube M. As said control potential is not delayed or retarded the indication of the tuning indicator tube M begins with the weakest transmitter. The control potential is fed to the control grid 1' over a filter element consisting of resistance R_6 and condenser C' . The control of the regulating grid 4' is performed over the voltage divider consisting of resistances R_1 , R_2 , R_3 , to which the screen grids of the preceding tubes are connected between resistances R_1 and R_2 . Between the resistances R_4 and R_5 which are connected in parallel to resistance R_1 of the voltage divider, there is located the tap for the plate potential of the multiple purpose tube D' and a variable tap on the resistance R_5 is connected to the plate of

indicator tube M. With signal reception the control grid of the tuning indicating tube becomes more negative due to the control potential produced by the right-hand diode path. As a result the current flowing in this portion decreases and opens the audio frequency portion of the multiple purpose tube D' due to the lower potential drop at resistance R_8 and due to the voltage increase at the top of the plate potential for the multiple purpose tube. Simultaneously a broadening of the light angle occurs corresponding to the signal. The control of the regulating grid 4' is performed also by the increase of the potential between resistances R_2 and R_3 .

The audio frequency voltage is taken off the diode load resistance R_{10} over resistance R_{11} and condenser C_{10} , and is fed to the volume control and compensated tone control network consisting of resistances R_{13} and R_{14} and condenser C_6 . The slider is connected to the grid of the multiple purpose tube D' through resistance R_{12} . The amplified audio frequency potential is fed from the plate of the multiple purpose tube to the control grid of the final amplifier tube E through the usual resistance-condenser coupling network.

In the arrangement according to Fig. 9, the incoming signal is rectified in the left-hand diode path of the rectifier D and the control potential is produced across the load resistance R_5 , said control potential being fed to the control grid 1' of tuning indicator tube M through resistance R_2 . The control potential effects, at the plate 6' of the tuning indicator tube M the voltage of which is taken off the voltage divider R_1 , R_2 , an increase in potential and thereby a broadening of the light angle. The cathode of the tuning indicator tube M and of the diode D have a negative auxiliary potential (-150 volts) over a common resistance R_4 bridged by condenser C_1 . The voltage drop of this resistance has to be so adjusted that the cathodes possess a small positive potential with respect to ground. If the above-mentioned control occurs, the potential drop of resistance R_4 decreases, that is the regulating grid 4' grounded over resistance R_8 becomes more positive in regard to the cathode whereby, on the one hand, the indication is assisted, and, on the other hand, the grid potential of the audio frequency tube N is driven over resistance R_7 , so that thereby the blocking of said tube is removed. The audio frequency voltage is taken off by means of the slider on the load resistance R_5 and is fed to the grid of the audio frequency tube N through condenser C_3 .

Fig. 10 represents a modified arrangement of Fig. 9. Instead of the diode D in the latter figure a multiple-purpose tube D' is used and a separate audio frequency tube is thereby saved. The radio frequency signal produces at the combination R_5-C_2 , through the rectified current, the control potential which is fed through the control grid 1' of indicator tube M through resistance R_3 . When a radio frequency signal is received the plate current of the tuning indicator tube M is decreased and thereby an increase in the potential across the voltage divider R_1-R_2 will occur and also a broadening of the light angle. Tuning indicator tube M and multiple-purpose tube D' have a common cathode resistance R_6 at negative potential. Exactly as in the arrangement according to Fig. 9 the control effects simultaneously a decrease in the voltage drop across resistance R_6 whereby the po-

tential of the regulating grid 4' becomes more positive and whereby the light angle is also increased. The decrease of the voltage drop across resistance R_6 also effects an increase in the potential of the point X on the voltage divider consisting of resistances $R_7-R_8-R_{10}$. In this instance the right-hand diode path becomes operative and the blocking of the audio frequency tube is removed. Resistance R_{12} and condenser C_8 effect the usual filtering of the plate current for the multiple-purpose tube at the external resistance R_{11} from which the amplified audio frequency potential is taken off through condenser C_5 . The taking off of the audio frequency upon rectification of the radio frequency in the diode path is performed over the slider of resistance R_5 , said slider being connected to the grid of the multiple-purpose tube through condenser C_4 , resistance R_8 serving as the grid leak for the control grid of said tube.

The control potential for the preceding tubes may be taken off the regulating grid 4' of the tuning indicator tube because when controlling the tuning indicator tube the voltage drop over resistance R_6 decreases and thereby the potential of the cathode so that from a given point the potential of the cathode in regard to the regulating grid becomes negative. This causes a grid current effecting a voltage drop over resistance R_4 , said voltage drop being able to be used for control. This control begins of course in a retarded manner as the cathode is positive in regard to the regulating grid before radio frequency signals are received.

Fig. 11 represents a simplification of the arrangement shown in Fig. 10. A separate diode rectifier is here omitted and is replaced by the control grid 1' and the regulating grid 4' of the tuning indicator tube M. Therefore, the output of band pass filter B_f is directly connected to the control grid of tuning indicator tube M and the audio frequency voltage across load resistance R_5 is taken off by way of resistance R_4 and condenser C_4 and fed to the grid of the audio frequency tube N, the signal grid whereof is connected by way of resistance R_5 to the regulating grid 4' of the tuning indicator tube M. When radio frequency is received grid current flows between control grid 1' and cathode of the tuning indicator tube so that a voltage drop occurs across resistance R_5 , said voltage drop negatively biasing the control grid of the tuning indicating tube M. This effects a decrease in plate current and therefore the usual increase in plate voltage and thus a broadening of the light angle. The cathodes of the two tubes M, N are connected to a negative auxiliary potential over a common resistance R_8 so that when regulating the regulating grid potential, said potential tends to assume more positive values and assist the indication. In the instance where the grid current begins to flow through the regulating grid, the blocking of the audio frequency tube N, the control grid of which is connected to the regulating grid over resistance R_6 , will be overcome. Simultaneously the voltage drop occurring across resistance R_8 may serve for retarded control of the preceding tubes.

In the circuit of Fig. 12 there is shown a tuning indicator tube M functioning as a rectifier of grid detection type. As in the circuit of the preceding figure, the decreasing plate current caused by rectification effects a broadening of

the light angle. The amplified audio frequency is taken off the external resistance R_1 over condenser C_2 and is fed to the succeeding amplifier stages. The cathode is connected to a negative auxiliary potential over resistance R_3 so that a control potential occurs, corresponding to the arrangement according to Fig. 11.

In the circuit according to Fig. 13 the tube preceding the indicator tube M is a hexode having the grids 1, 2, 3, 4, and acting as a pentode. The radio or intermediate frequency is fed over a band pass filter B_f to grid 1 and is taken off in amplified form at the plate circuit L_1-C_1 over condenser C_2 . It is then fed to the plate of the hexode. Between the grid 4 and the plate there is produced a space charge which forms a virtual cathode for the plate. The plate therefore operates as diode plate and is connected accordingly. The control and audio frequency potential resulting developed across resistance R_4 is fed to the control grid of indicator tube M through a filter network consisting of series resistances R_5 and R_6 and shunt condenser C_4 . The voltage increase occurring through the control action across resistance R_7 will again increase the light angle. The cathode of the tuning indicator tube M is at a negative auxiliary potential by way of the resistance R_8 so that the voltage curve of the regulating grid described in Fig. 11 results and a retarded control potential is produced over resistances R_8-R_{10} , said control potential being fed if desired to the preceding tubes. Resistances R_1 and R_2 form the voltage divider for applying potential to the screen grid 2 of the hexode while resistance R_{11} forms the grid leak resistance of the following tube, not shown. The grid 3 is the suppressor and is connected in the usual manner to the cathode.

Fig. 14 shows a pentode tube V. The screen grid voltage divider consisting of resistances R_1 , R_2 , R_3 , and R_4 controls the regulating grid 4' by way of resistance R_7 . The amplifier system of the tuning indicator tube M is used in this case for plate rectification. The audio frequency is taken off plate resistance R_9 through condenser C_3 and the control potential for the preceding tubes is produced across the voltage divider consisting of the resistances R_5 , R_6 , R_8 .

In this arrangement of the tuning indicator tube, contrary to the arrangements described above, the light angle is influenced through the control bridge in a direction opposite to those of the preceding arrangements. To be sure, in a plate rectifier the plate current increases with increasing radio frequency potential and thus also the voltage drop over the external resistance R_9 so that the plate potential decreases. This effects, as mentioned above, a narrowing of the light angle. The second control of the light angle occurring over the regulating grid effects however, due to its voltage curve, an increase of the light angle. As the last mentioned control influences the light angle much more than the first one, its effect is overwhelming and the light angle will increase also when radio frequency is received, although with a somewhat decreased sensitivity.

In the arrangement according to Fig. 15, the radio frequency is fed to the plates of diode D through a band pass filter B_f , the left-hand plate of said diode serving for demodulation in connection with resistance R_1 and condenser C_2 .

The audio frequency is taken off the slider of resistance R_1 and is fed to the grid of tube V through condenser C_3 . The second diode plate has radio frequency impressed thereon by way of the condenser C_1 and serves for producing the control potential of the preceding tubes in connection with resistance R_2 . A selective tuning circuit S is coupled to the band pass filter Bf , said tuning circuit having its damping additionally removed by feedback. The control grid $1'$ of the indicator tube operates again as a diode plate. When radio frequency is received indication sets in with very selective tuning of the receiver only, corresponding to the selectivity of tuning circuit S due to the voltage drop over resistance R_8 bridged by condenser C_8 . The cathodes of all tubes are connected to a negative auxiliary potential over a common resistance R_7 , so that, in regard to the regulating grid $4'$ the same holds true as in the arrangement according to Fig. 11.

In the arrangement according to Fig. 16, the intermediate frequency is fed through the selective tuning circuit S , the damping of which is additionally removed by feedback, to the control grid $1'$ of the tuning indicator tube M , said grid operating again as diode plate. The plate potential of said tube is derived from a voltage divider consisting of resistances R_1 , R_2 , R_3 , one end of which is connected to the negative auxiliary potential. The potential increase occurring over resistance R_1 controls the light angle and also the regulating grid $4'$ which is connected to the third grid of a hexode. The grid current setting in with a given signal amplitude, (adjustable over resistance R_1) varies the potential of resistance R_3 and thereby removes the blocking of the intermediate frequency hexode N . The second band pass filter Bf_2 circuit controls in the usual manner a diode path producing a control potential over resistance R_9 , said potential being fed to the first grid of the hexode over a filter section consisting of resistance R_8 , condenser C_5 and resistance R_7 . Said potential may be branched off resistance R_8 and used for

the control of further tubes. The first grid of the hexode is coupled through condenser C_3 to the second circuit B of the band pass filter Bf_1 . The amplified intermediate frequency is taken off band pass filter Bf_2 at the plate side and is fed to the second or right hand path of the diode D . The audio frequency is taken off load resistor R_{10} and may be fed to further amplifier stages.

The above-described circuits show the various ways in which a combination tube according to the invention can be utilized. The enumeration is obviously without limit, and other circuits of different construction can be envisaged. In the description of the circuits, emphasis was laid solely on the especially interesting points in connection with the combination tube. The other circuit elements are those which are readily understood by anyone skilled in the art, and are shown to elucidate the manner in which the circuits according to the invention can be employed.

What is claimed is:

A circuit arrangement for the visual indication of voltages and for indicating the degree of tuning in radio apparatus, comprising an electron discharge tube containing an indicating section and an amplifying section, the latter including at least an anode, the indicating section comprising a cathode and a surrounding anode electrode rendered fluorescent by the action of the impinging electrons, a control electrode in the form of a rod positioned between the fluorescent anode and the cathode and having a connection to the amplifier anode, and a shield grid within the cathode-anode space having a suitable potential impressed thereon to form a control space surrounding the cathode whereby the potential and the field intensity in the vicinity of the control electrode are decreased, and circuit means responsive to the received signal for applying a suitable potential on said shield grid for regulating the effect of said control space.
